WILLIAM W. LASKER, OF BROOKLYN, NEW YORK, ASSIGNOR TO POWERS ACCOUNTING MACHINE COMPANY, OF NEW YORK, N. Y., A CORPORATION OF DELAWARE.

RIBBON-REVERSE MECHANISM.

1,249,640

Specification of Letters Patent. Patented Dec. 11, 1917.

Application filed September 17, 1915. Serial No. 51,153.

To all whom it may concern:

Be it known that I, WILLIAM W. LASKER, a citizen of the United States, residing in Brooklyn, in the county of Kings and State of New York, have invented certain new and useful Improvements in Ribbon-Reverse Mechanisms, of which the following is a specification.

This invention relates to a mechanism for reversing a ribbon on a printing machine such as an accounting machine, typewriter, or the like.

The main object of the present invention is to provide an improved reversing mechanism for printing ribbons which mechanism is positive in initiating its reverse movement, is characterized by its simplicity and small number of working parts, and can be actuated both manually and mechanically without special adjustment.

These and other features, capabilities and advantages of the invention will appear from the subjoined detail description of one specific embodiment thereof illustrated in the accompanying drawings in which—

Fig. 1 is a side elevation of an accounting machine with parts broken away to illustrate the ribbon reversing mechanism; and Fig. 2 is a fragmental plan view of the same.

Fig. 3 is a front elevation of an accounting machine with parts broken away to illustrate the ribbon reversing mechanism.

Fig. 4 is a fragmental perspective of a part of the ribbon reversing mechanism.

Fig. 5 is a perspective view of the pin to which the end of the ribbon is attached.

Fig. 6 is a plan view of the spool on which the ribbon is wound.

Fig. 7 is a transverse section of the spool shown in Fig. 6.

Fig. 8 is a perspective showing the clip secured to the end of the ribbon by means of which the ribbon is attached to the pin shown in Fig. 5.

In the present embodiment two vertical shafts 21 are provided properly journaled at their upper portions in the brackets 22 and at their lower portions in the plate 23, the shafts 21 terminating at their lower ends in beveled gears 24 disposed below the plate 23, which gears are meshed with the beveled gears 25, one gear 25 being fixed on the horizontally disposed shaft 26, and the other

gear 25 being fixed on the horizontally disposed shaft 27. The inner end of the shaft 26 is disposed in a bearing 28 and the inner end of the shaft 27 is supported by the bearing 29 between which bearings the shafts 26 and 27 are each provided with a star-wheel 30. The outer ends of the shafts 26 and 27 are journaled in brackets 31 secured to the lower side of the plate 23. The plate 23 at each of its ends is provided with a hub 33 at the end thereof, through which extends a stub-shaft 34 having a collar 35 fixed to the upper end from one side of which extends a finger 36, (see Fig. 4), and the lower end of the stub-shaft is provided with a finger 37 extending forwardly under the plate 23 and having a downwardly projecting portion 38. A plate 39, which extends under and parallel to the plate 23, is slidably supported by brackets 40 extending downwardly from the plate 23. There is provided an orifice near each end of said plate 39 with which the downwardly extending portions 38 register and co-operate. The fingers 36 engage the lower ends of and are disposed in the path of movement of such lower ends of the levers 43 fulcrumed substantially in their middle portions to the main frame of the machine. The upper ends of the levers 43 are provided with fingers 44 extending under the lower disks of the ribbon spools 45 which are fixed on the upper ends of the shafts 21 above the brackets 22, such shafts being provided with cranks 46 at their upper ends, having handles 47, by means of which the spools 45 may be manually rotated. The spools are each provided with slots 48 extending substantially radial and parallel with one another in the disks of the spools 45. In each pair of such slots 48 there is disposed a pin 49 having a lower extension 50 adapted to engage the finger 44 of a lever 43. The pins 49 are guided between the disks of the spools 45 by means of small disks 41 (Fig. 5). Adjacent to the spools 45 there are provided brackets 51 each having a vertically extending plate 52 disposed alongside of a spool 45 and adapted to guide the ribbon from such spool to the idler 53, which latter serves as a guide for changing the course of the ribbon moving from such spool 45. The brackets 51 are furthermore provided with guiding rolls 54 adapted to ride in the slots 55 formed in the extensions

56 at the upper ends of the levers 43 for guiding such upper ends of the levers 43.

On the main driving shaft 57 there is fixed a bracket 58 having a slot 59 therein to receive a pin of the lever 60 loosely journaled on the shaft 57 by means of which pin and slot connection the lever 60 is oscillated. The lower end of the lever 60 has pivotally connected thereto two arcuate segments 61 each 10 having a series of teeth on its inner edge adapted to engage with one of the star wheels 30, each segment independent of the other. The segments 61 are provided with curved slots 62 to permit the passage of the 15 cam block 63 therethrough, which cam block 63 is secured to the plate 39. The plate 39 is also provided with two springs 64 each engaging one of the segments 61 and exercising an upward pressure on the same so that the 20 spring 64 will flex or maintain in engagement with its star wheel 30, that segment 61 which is not engaged by the cam block 63.

The operation is as follows:

The shaft 57 is driven by any suitable 25 source of power and with every oscillation of the shaft 57 the lever 60 will be oscillated and swing the segments 61 with it. While the ribbon on the spools 45 is going in one direction, the cam 63 will be disposed in one 30 slot 62 and maintain its segment 61 out of engagement with its star-wheel 30, while the other segment 61 is in engagement with the star-wheel so that upon the oscillation of the shaft 57 such other star-wheel 30 will be 35 rotated, the star-wheel having inclining teeth so that upon the return movement of the segment or when it is manually operated, the segment will merely slide over such inclined teeth. When the ribbon on a spool 40 45 comes to its end which is secured in a clip 65, (see Fig. 8) which clip has laterally-bent arms 66 by means of which the end of the ribbon is firmly clamped against the clip 65 and which clip also has a hook 67 at its 45 extreme end adapted to engage the pin 49 in the spool 45, the further movement or pull of the ribbon will draw the pin 49 to the outer ends of the slots 48 and while so moving outwardly such pin 49 will strike the 50 finger 44 of the lever 43, swinging the lever 43 so that its lower end will engage the finger 36 and rotate the shaft 34, which in turn, by means of its finger 37, will slide the plate 39 and thereby move the cam-block 63 out of 55 the slot 62 of the one segment 61 into the slot 62 of the other segment 61.

Since the rotation of the star-wheels 30 will rotate either the shaft 26 or 27 and such shaft 26 or 27, by means of the beveled gears 60 connected thereto, is respectively connected to rotate one of the shafts 21 and the thereto connected spool 45, the change of drawing one segment 61 from one star-wheel 30 and advancing the other segment 61 into engagement with the other star-wheel 30, will

switch off the driving mechanism drawing the ribbon in one direction to the other driving mechanism for drawing the ribbon in the other direction and thus reverse the direction of movement of the ribbon.

70

Formed on the main frame are flat springs 68 engaging and exercising tension on the shafts 21 so that when either shaft is not being driven by its star-wheel 30, such shaft will not be rotated at a quicker movement 75 than the ribbon is being drawn and thus buckle up the ribbon.

75

It is obvious that various changes and modifications may be made to the details of construction without departing from the 80 general spirit of the invention.

I claim:

1. In a reversing mechanism for a printing ribbon, the combination with a frame, two ribbon supporting members rotatably 85 mounted therein, means for attaching the ends of the ribbon to said supporting members, a main driving shaft, connecting means each operatively connecting one ribbon supporting member with said driving shaft, a cam for disconnecting said connecting means one to the exclusion of the other so that only one ribbon supporting member can be rotated at any one time, a bar on which said cam is mounted, and means for connecting 90 the bar with the ends of said ribbon to be actuated by that end of the ribbon which becomes free when the spool upon which it is disposed becomes unwound.

95

2. In a reversing mechanism for a printing ribbon, the combination with a frame, two spools rotatably mounted in said frame, the ends of the ribbon being attached to said spools, a star-wheel operatively connected with each spool, a main driving shaft, an 100 arm loosely mounted on said driving shaft, links pivotally connected to said arm each disposed adjacent to one of said star-wheels, teeth on said links, means for oscillating said arm with said main driving shaft, and 105 means for maintaining the teeth of said links in engagement with said star-wheels one to the exclusion of the other so that only one spool can be positively rotated at any one time.

110

3. In a reversing mechanism for a printing ribbon, the combination with a frame, two spools rotatably mounted in said frame, a star-wheel operatively connected with each spool, a main driving shaft for rotating said 120 star-wheel, an arm loosely mounted on said driving shaft, links pivotally connected to said arm each disposed adjacent to one of said star-wheels, teeth on said links, a bracket fixed to said main driving shaft, 125 there being a slot in said bracket, a pin on said arm traveling in said slot whereby said arm is oscillated with said main driving shaft, and means for maintaining the teeth of said links in engagement with said star- 130

wheels one to the exclusion of the other so that only one spool can be positively rotated at any one time.

4. In a reversing mechanism for a printing ribbon, the combination with a frame, two spools rotatably mounted in said frame, the ends of the ribbon being connected to said spools, a star-wheel operatively connected with each spool, a main driving shaft, an arm loosely mounted on said driving shaft, links pivotally connected to said arm each disposed adjacent to one of said star-wheels, teeth on said links, means for oscillating said arm with said main driving shaft, there being slots in said links, a plate slidably mounted under said star-wheels and extending through the slots of said links, springs on said plate for normally maintaining said links in mesh with said star-wheels, and a cam on said plate adapted to pass through the slots of said links and adapted to be disposed in one slot to the exclusion of the other according to the position of said plate whereby the link it engages will be maintained in mesh with its star-wheel. 70
5. In a reversing mechanism for a printing ribbon, the combination with a frame, two spools rotatably mounted in said frame, the ends of the ribbon being connected to said spools, a star-wheel operatively connected with each spool, a main driving shaft, an arm loosely mounted on said driving shaft, links pivotally connected to said arm each disposed adjacent to one of said star-wheels, teeth on said links, means for oscillating said arm with said main driving shaft, there being slots in said links, a plate slidably mounted under said star-wheels and extending through the slots of said links, springs on said plate for normally maintaining said links in mesh with said star-wheels, a cam on said plate adapted to pass through the slots of said links and adapted to be disposed in one slot to the exclusion of the other according to the position of said plate whereby the link it engages will be maintained in mesh with its star-wheel, and means for connecting said spools with said plate whereby said plate will be shifted whenever the ribbon is completely unwound from one spool so as to release the star-wheel thus far disconnected and disconnect the other star-wheel. 75
6. In a reversing mechanism for a printing ribbon, the combination with a frame, two spools rotatably mounted in said frame, vertical shafts on which said spools are fixed, gears on said shaft, star wheels, horizontal shafts on which said star-wheels are fixed, gears on the end of said horizontal shafts in mesh with the gears of said vertical shafts, a main driving shaft for rotating said star-wheel, an arm loosely mounted on said driving shaft, links pivotally connected to said arm each disposed adjacent to one of said star-wheels, teeth on said links, means for oscillating said arm with said main driving shaft, there being slots in said links, a plate slidably mounted under said star-wheels and extending through the slots of said links, springs on said plate for normally maintaining said links in mesh with said star-wheels, a cam on said plate adapted to pass through the slots of said links and adapted to be disposed in one slot to the exclusion of the other according to the position of said plate whereby the link it engages will be maintained in mesh with its star-wheel, and means for connecting said spools with said plate whereby said plate will be shifted whenever the ribbon is completely unwound from one spool so as to release the star-wheel thus far disconnected and disconnect the other star-wheel. 80
7. In a reversing mechanism for a printing ribbon, the combination with a frame, two spools rotatably mounted in said frame, the ends of the ribbon being attached to said spools, vertical shafts on which said spools are fixed, gears on said shafts, star wheels, horizontal shafts on which said star-wheels are fixed, gears on the end of said horizontal shafts in mesh with the gears of said vertical shafts, a main driving shaft, an arm loosely mounted on said driving shaft, links pivotally connected to said arm each disposed adjacent to one of said star-wheels, teeth on said links, means for oscillating said arm with said main driving shaft, and means for maintaining the teeth of said links in engagement with said star-wheels one to the exclusion of the other so that only one spool can be positively rotated at any one time. 85
8. In a reversing mechanism for a printing ribbon, the combination with a frame, two spools rotatably mounted in said frame, a main driving shaft, means for connecting said spools to rotate with said shaft, an arm loosely mounted on said driving shaft, links pivotally connected to said arm and each operatively connected to one of said connecting means, means for oscillating said arm with said driving shaft, and means for maintaining said links in operative engagement with said connecting means one to the exclusion of the other so that only one spool can be positively rotated at any one time. 90
9. In a reversing mechanism for a printing ribbon, the combination with a frame, two spools rotatably mounted in said frame, radial slots in said spools, pins slidably mounted in said slots, the ends of the ribbon being connected to said pins, said pins being normally maintained at the inner ends of said slots but being pulled to the outer end of the slot of that spool from which the ribbon has been completely unwound, a driving shaft for rotating said spools independently, means for connecting said spools with said shaft one to the exclusion of the other, and a cam operatively connected with said pins to shift said disconnecting means so that it will permit rotation of one spool at 105 the time and disconnect the other spool. 110
10. In a reversing mechanism for a printing ribbon, the combination with a frame, two spools rotatably mounted in said frame, a main driving shaft, means for connecting 115

said spools to be rotated with said main driving shaft, means for disconnecting said connecting means, one to the exclusion of the other, and means for connecting said spools with said disconnecting means whereby said disconnecting means will be shifted, said means comprising slots radially disposed in said spools, pins slidably mounted in said slots, the ends of the ribbon being connected to said pins, levers fulcrumed adjacent to said spools, fingers on said levers disposed in

the path of movement of said pins when said pins are disposed in the outer ends of their slots thereby to engage said levers and swing the same, other fingers operatively connecting 15 said levers to said disconnecting means so that the actuation of said first mentioned fingers by said pins will shift said disconnecting means.

WILLIAM W. LASKER.
